CLAIM

The ornamental design for a weather station, as shown and described.

DESCRIPTION

FIG. 1 is an upper perspective view of a weather station; FIG. 2 is a lower perspective view of the weather station of FIG. 1;

FIG. 3 is a front view of the weather station of FIG. 1; FIG. 4 is a rear view of the weather station of FIG. 1; FIG. 5 is a right side view of the weather station of FIG. 1;

FIG. 6 is a left side view of the weather station of FIG. 1; FIG. 7 is a top side view of the weather station of FIG. 1; and, FIG. 8 is a bottom side view of the weather station of FIG. 1.

The broken lines shown in the figures are for the purpose of illustrating boundaries and form no part of the claimed design.
